[57] **CLAIM**

The ornamental design for a magnetic water conditioner for water conveying conduits, as shown and described.

DESCRIPTION

FIG. 1 is a perspective view of a magnetic water conditioner for water conveying conduits showing our new design;

FIG. 2 is a front elevational view thereof, the rear view being a mirror image;

FIG. 3 is a left side elevational view thereof; the right side being a mirror image; and,

FIG. 4 is a top plan view thereof, the bottom view being identical.

FIG. 1

FIG. 2

FIG. 3

FIG. 4
